WATERPROOFED BUILDING
CONSTRUCTION

Allan Cheney, Cynwyd, Pa.

Application December 21, 1938, Serial No. 247,119

18 Claims. (Cl. 72—127)

The present invention relates to improvements in waterproofed building constructions, particularly to buildings constructed in whole or in part of concrete. More particularly, the invention aims to provide new means and combinations of means for effectively waterproofing spandrel beams of such buildings.

The desirability of waterproofing spandrels like parts of concrete or partly concrete buildings has long been recognized by builders and architects. Heretofore, several different waterproofing materials have been proposed for this purpose and then have usually comprised one or more layers of fabric, felt or paper saturated with a waterproofing compound, preferably bitumen, the sheet being laid so that it overlies the top or outer side of the spandrel beam. More recently such materials have been combined with a very thin layer of electro-deposited copper intended to render the sheeting more waterproof.

The use of such prior membranes with or without an electro-deposited copper surface has only been partially satisfactory. Failure of such prior devices has been due to the fact that all of such material disintegrates more or less, when imbedded in a masonry joint, to the end that the waterproofing is not permanent. Furthermore, the application of such membranes is costly in that the plastic cement in which the membranes are laid is applied by the waterproofing contractor with the result that the waterproof and masonry are often in conflict, one workman being delayed by the other. Furthermore, membrane waterproofing is relatively thin, subject to easy puncture and, as it has been laid over the top and side faces of spandrel beams, a considerable amount of material is required with proportionately relatively high cost. As a result, many architects are extremely doubtful as to the value of such waterproofing as compared to the cost.

Also, where a brick or stone veneer is used, a shelf angle is provided to support the veneer immediately above the door and window openings and the membrane is usually carried across the top and down the face of the beam so that no bond is possible between the veneer and the beam, with the result that the veneer merely rests or floats against the beam without any mechanical interlock.

With a view to overcoming the above stated and other objections, my invention provides a new means and combination of means suitable for waterproofing buildings and particularly spandrel and like beams comprising a flashing installation that is permanent, effective, secure,

and one that may be installed at a substantial saving in cost.

My invention is more fully explained by referring to the accompanying drawings which are intended merely as illustrative of the invention.

In the drawings—

Fig. 1 is a detail sectional view illustrating one manner of using the invention in a building construction;

Fig. 2 is an enlarged detailed view thereof;

Fig. 3 is a detail view illustrating the manner of attaching the reglet to a form when used with concrete masonry;

Fig. 4 is a detail view of the cap flashing;

Fig. 5 is a sectional view illustrating one manner of using the invention in connection with a roof flashing; and

Figs. 6 to 13 illustrate modified forms of reglets according to the invention.

In the construction of masonry buildings it is highly desirable to provide a waterproof cut-off in the masonry wall, continuously around the entire building, at approximately each floor level and above the ceiling level, and also above openings such as door and window openings. In the case of masonry buildings constructed wholly or in part of concrete, the spandrel beam extends from the opening upwardly to approximately the next floor level and it is desirable to provide against the infiltration of moisture downwardly around it. As stated above, this has heretofore been accomplished by covering the spandrel beam with a membrane waterproofing applied by a plastic cement, the membrane covering the upper and outer exposed surfaces thereof.

In Fig. 1 there is illustrated such a building construction which may comprise a spandrel beam 10 of concrete, an exterior wall 11, the spandrel beam 10 extending from an opening 12 upwardly to the level of the sub-floor 13. The finishing floor 14, composed of any suitable material is, of course, laid upon the sub-floor. The main portion of the exterior wall 11 may be carried by the spandrel beam and a veneering 15 of brick or stone may overlie the outer vertical face of the spandrel beam between the opening 12 and floor line being supported on a shelf angle 16.

The spandrel beam 10 may be formed in any conventional manner by pouring concrete into a wooden form 18 which is removed after the spandrel beam is thoroughly set.

According to my invention, the spandrel beam may be fully and adjustably protected from moisture of infiltration by installing a through-wall

flashing 25 on the upper surface thereof extending from the inside of the wall 26 to the outer edge of the building, this flashing 25 serving to cut off infiltration through the wall and consequent damage to the ceiling and upper interior walls below. The lower part of the spandrel beam may be protected by a counter-flashing 27 overlying the shelf angle 16 and extending upwardly beyond the lower edge of the spandrel beam 10. Preferably the upper edge of the counter flashing 27 is inturned and imbedded into the spandrel beam 10 to prevent the seepage of moisture between the shelf angle and spandrel beam. The flashing adequately prevents infiltration of moisture past the lower edge of the spandrel to the door or window framework in the opening 12.

The flashing 25 is preferably laid in mortar on the upper surface of the spandrel beam 10 and is formed with an upturned inner edge to cause the seepage of moisture to drain to the exterior of the wall. The flashing 25 preferably is of the type generally known in the trade as mechanically keyed flashing, capable of being bonded to the mortar against movement longitudinally, transversely and vertically, and advantageously is of the construction shown in my Patents 1,715,000 and 1,871,585.

It will, of course, be apparent that the counter flashing 27 may be as deep as desired so that it may extend upwardly along the vertical faces of the beam 10 to the desired height. However, I find that the best results are secured when the counter flashing 27 extends above the lower edge of the spandrel a minimum distance only as this adequately waterproofs the lower part of the spandrel where seepage is likely, and at the same time leaves the vertical face of the spandrel beam available for a masonry tie for the veneering 15.

A further feature of my invention resides in the provision of an improved reglet and cooperating counter-flashing, which reglet and counter-flashing are highly suitable for use as the lower spandrel flashing above described.

According to this feature of the invention a sheet metal reglet, preferably of copper, is formed with a base 30, an upwardly inclined slotted portion 31 adjacent one end, and an in-turned anchor and water stop 32 adjacent the other end. The slotted portion 31 may be formed of spaced walls extending upwardly at an angle of substantially 45° to the base 30, one wall of which is preferably formed with a series of notches 33 adapted for locking engagement with a cooperating part of a counter-flashing 27. The counter-flashing 27 may advantageously be formed with a plain face 35, an angular extension 36 adapted to be positioned in the slotted portion 31, and a reversely bent hooked end 37 adapted for self-locking engagement with one of the notches 33. Thus the counter-flashing may be quickly and readily installed by locking the end 37 in one of the notches 33 insuring a secure installation with the vertical portion 35 of the counter-flashing 27 lying flush against the shelf angle to be protected.

The reglet may readily be installed in place by lightly nailing it to the inside of one of the temporary forms prior to the pouring of concrete, as illustrated in Fig. 3. After the concrete part has been poured and has become set, the temporary form 18 may be removed without displacement of the reglet, as both the slotted portion 31 and 32 serve as anchors. The protruding

75 nail ends may then be clipped, leaving an undisturbed reglet slot in the concrete section.

The improved reglet and counter-flashing construction above described is not limited in use to spandrel flashing as illustrated in Figs. 1 and 2, but may also be imbedded in a concrete parapet wall 40 (Fig. 5), and all concrete walls rising above roof surfaces requiring a counter-flashing 41. Under this system a built-up felt base flashing 42 or a copper base flashing can be installed and the counter-flashing 41 may then be locked in the reglet, which, due to its construction, is sufficiently flexible as to allow for necessary settlement or shrinkage of the base flashing and expansion and contraction between the base flashing 42 and the counter-flashing 41.

In the above respects the improved reglet and counter-flashing construction is of great advantage as it permits of ready tightening after the base flashing has shrunk and settled in place.

In Figs. 6 to 13 I have indicated by way of illustration, various means for effecting an adjustable self-locking action between the tongue end 37 of the counter-flashing 27 and the slotted reglet.

25 Preferably the slotted portion of the reglet is formed with a series of saw-tooth or Z-notchings 50 and the cooperating tongue end 37 may be formed with a simple reverse bend as shown in Fig. 6. The Z-shaped notches 60 may be formed in the upper wall of the slot as shown in Fig. 6 or in the lower as shown in Fig. 7, and they may extend downwardly from the upper wall of the slot as shown in Fig. 8. Alternately the notches 35 may be formed as channels 51, extending upwardly from the upper wall of the slot as in Fig. 9 or depending therefrom, as in Fig. 10, or the notches may be formed by a series of points 52 punched downwardly from the upper wall of 40 the slot, as in Fig. 11.

Furthermore, both faces of the slot may be notched either in the form of arcuate corrugations 53, as in Fig. 12, or Z-shaped, as in Fig. 13, and if desired, the tongue end of the counter-flashing may be formed with hooked ends bent alternately in opposite directions.

It will be clear that my improved reglet and counter-flashing may be used generally wherever reglets are required.

50 Advantages of the invention reside in the provision of a simple permanent and efficient spandrel flashing that may readily be installed in the building by the mason, as the building is erected, resulting in a considerable saving in the cost of providing spandrel waterproofing. The improved reglet is adaptable for securing counter-flashing to molded surfaces and has the important advantage that the counter-flashing may be quickly locked in desired position merely by forcing the hooked end of the counter-flashing into the notched slot of the reglet. The parts are therefore self-locking, and may be locked in one of several adjusted positions.

It will be apparent to those skilled in the art 65 that the several features of the invention are not restricted to the specific forms shown in the drawings which are intended merely as illustrations of some manners of using the invention.

I claim:

1. A masonry building comprising a spandrel beam, a wall section supported on said spandrel beam, a veneer section overlying the vertical face of said spandrel beam, a layer of mortar between said spandrel beam and said wall and said veneer, a continuous sheet metal throughwall flashing

of desired width to extend entirely through said wall embedded in the layer of mortar between said wall and spandrel beam and mechanically keyed thereto, and serving as a moisture cut-off immediately above said spandrel beam, and a sheet metal cap flashing secured to the lower part of said spandrel beam and extending downwardly between the spandrel beam and veneer.

2. A masonry building comprising a spandrel beam, a wall section supported on said spandrel beam, a veneer section overlying the vertical face of said spandrel beam, a layer of mortar between said spandrel beam and said wall and said veneer, a continuous sheet metal throughwall flashing of desired width to extend entirely through said wall embedded in the layer of mortar between said wall and spandrel beam and mechanically keyed thereto, and a sheet metal cap flashing secured to the lower part of said spandrel beam and extending downwardly between the spandrel and veneer, the veneer being bonded to the spandrel by brick ties or stone ties.

3. A masonry building comprising a spandrel beam, a wall section supported on said spandrel beam, a veneer section overlying the vertical face of said spandrel beam, a layer of mortar between said spandrel beam and said wall and said veneer, a continuous sheet metal throughwall flashing of desired width to extend entirely through said wall and outwardly beyond the spandrel beam embedded in the layer of mortar between said wall and spandrel beam and mechanically keyed thereto and serving as a moisture cut-off immediately above said spandrel, and a sheet metal cap flashing secured to the lower part of said spandrel and extending downwardly between the spandrel and veneer.

4. A masonry building comprising a spandrel beam, a wall section supported on said spandrel beam, a veneer section overlying the vertical face of said spandrel, a layer of mortar between said spandrel and said wall and said veneer, a continuous sheet metal throughwall flashing of desired width to extend entirely through said wall embedded in the layer of mortar between said wall and spandrel beam and mechanically keyed thereto, and serving as a moisture cut-off immediately above said spandrel beam, and a sheet metal cap flashing secured to the lower part of said spandrel and extending downwardly between the spandrel and veneer, said cap flashing having its upper end inturned and secured in said spandrel.

5. A masonry building comprising a spandrel beam, a wall section supported on said spandrel beam, a veneer section overlying the vertical face of said spandrel beam, a shell supporting said veneer, a layer of mortar between said spandrel beam and said wall and said veneer, a continuous sheet metal throughwall flashing of desired width to extend entirely through said wall embedded in the layer of mortar between said wall and spandrel beam and mechanically keyed thereto and serving as a moisture cut-off immediately above said spandrel beam, and a sheet metal cap flashing secured to the lower part of said spandrel beam and extending downwardly between the spandrel beam and veneer to said shelf.

6. A masonry building comprising a spandrel beam of molded cementitious material, a wall section supported on said spandrel beam, a veneer section overlying the vertical face of said spandrel beam, a layer of mortar between said spandrel beam and wall and said spandrel beam

and veneer, a continuous sheet metal flashing embedded in the mortar layer and extending from the inside of said wall to the outside thereof, a shelf below said spandrel beam supporting said veneer, and a sheet metal cap flashing secured to said spandrel beam, said flashing extending downwardly between the spandrel beam and veneer to said shelf.

7. A building construction as defined in claim 6 in which a sheet metal reglet is embedded in said spandrel beam and said cap flashing is secured in said reglet.

8. A building construction as defined in claim 6 in which a sheet metal reglet is embedded in said spandrel beam and said cap flashing is mechanically locked in said reglet.

9. In a flashing for buildings, a sheet metal reglet, a flashing cooperating therewith, and cooperating interlocking means on said flashing and reglet for mechanically locking said flashing in said reglet in one of a plurality of adjusted positions without the use of additional fastening devices.

10. In a flashing for buildings, a sheet metal reglet comprising a base, an angularly extending hollow extension opening into said base, a flashing cooperating with said reglet and formed with an angularly disposed portion adapted to enter said extension, a plurality of notches in said hollow extension, and a locking tongue on the angularly disposed end of said flashing adapted for self-locking engagement selectively with one of said notches.

11. In a flashing for buildings, a sheet metal reglet comprising a base, an angularly extending hollow extension opening into said base, a flashing cooperating with said reglet and formed with an angularly disposed portion adapted to enter said extension, a plurality of Z-shaped notches in said hollow extension, and a locking tongue on the angularly disposed end of said flashing adapted for self-locking engagement selectively with one of said notches.

12. In a flashing for buildings, a sheet metal reglet comprising a base, an angularly extending hollow extension opening into said base, a flashing cooperating with said reglet and formed with an angularly disposed portion adapted to enter said extension, a plurality of Z-shaped notches formed in the upper face of said hollow extension, and a locking tongue on the angularly disposed end of said flashing adapted for self-locking engagement selectively with one of said notches.

13. In a flashing for buildings, a sheet metal reglet comprising a base, an angularly extending hollow extension opening into said base, a flashing cooperating with said reglet and formed with an angularly disposed portion adapted to enter said extension, a plurality of Z-shaped notches formed in the lower face of said hollow extension, and a locking tongue on the angularly disposed end of said flashing adapted for self-locking engagement selectively with one of said notches.

14. In a flashing for buildings, a molded supporting body, a sheet metal reglet adapted to be molded into said supporting body, said reglet having a base adapted to be disposed flush with one face of said body, a hollow extension embedded in said body and disposed angularly with respect to said base, a cooperating sheet metal flashing having a part adapted to extend into said hollow extension, and cooperating interlocking means in said extension and on said flashing

part adapted for self-locking engagement upon insertion of said part into said extension.

15. A flashing for buildings as defined in claim 14 characterized in that the cooperating interlocking means are formed by one or more notches in the extension, and a reversely bent tongue on the flashing part.

16. A flashing for buildings as defined in claim 14 characterized in that the cooperating interlocking means are formed by a series of depending projections extending into said hollow extension and a reversely bent tongue on said flashing

part adapted, on insertion in the extension, to lie behind at least one of said projections.

17. A flashing for buildings as defined in claim 14 characterized in that interlocking means mechanically lock the flashing in the reglet without the use of additional fastening devices.

18. A flashing for buildings as defined in claim 14 characterized in that interlocking means mechanically lock the flashing in the reglet in one of a plurality of adjusted positions without the use of additional fastening devices.

ALLAN CHENEY.
